(57) **CLAIM**

The ornamental design for a display screen of a computing device with graphical user interface, as shown and described.

DESCRIPTION

The single FIGURE is a front view of a display screen of a computing device with graphical user interface in some embodiments.

The broken lines showing a display screen is included for the purpose of illustrating an environment of the claimed design and forms no part thereof. The remaining broken lines in the drawings illustrate portions of the graphical user interface that form no part of the claimed design.

1 Claim, 1 Drawing Sheet
